UNITED STATES PATENT OFFICE.

EMILE ROLLE, OF FRONTENAC, KANSAS.

SPARK-PLUG ATTACHMENT.

1,131,556.

Specification of Letters Patent.

Patented Mar. 9, 1915.

Application filed February 13, 1914. Serial No. 818,522.

To all whom it may concern:

Be it known that I, EMILE ROLLE, a citizen of the United States, residing at Frontenac, in the county of Crawford and State of Kansas, have invented certain new and useful Improvements in Spark-Plug Attachments; and I do hereby declare the following to be a full, clear, and exact description of the invention, such as will enable others skilled in the art to which it 10 pertains to make and use the same.

My invention relates to new and useful improvements in spark plugs and more particularly to an attachment therefor which 15 will prevent accumulation of carbon at the sparking points and insure the proper combustion of the gases within the engine cylinder.

An important object of my invention is 20 to provide a simple and inexpensive attachment for spark plugs which may be readily attached to plugs and which will prevent accumulation of carbon and other foreign matter on the electrodes of the plug.

Another important object of my invention is to provide a device of the character described which is simple as to construction, reliable and efficient in operation, and 25 cheap to manufacture.

The above and additional objects are accomplished by such means as are illustrated in the accompanying drawings, described in the following specification and then more particularly pointed out in the claims which 30 are appended hereto and form a part of this application.

With reference to the drawings, wherein I have illustrated the preferred embodiment of my invention as it is reduced to practice, 40 and throughout the several views of which similar reference numerals designate corresponding parts: Figure 1 is a side elevation showing my attachment attached to a spark plug, Fig. 2 is a longitudinal sectional view showing my attachment in operative attached position, Fig. 3 is a detail side elevation of the conical protecting cap for the electrodes of the plug, Fig. 4 is a detail perspective view of the holder for the cap, 45 and Fig. 5 is a detail perspective view of a slightly modified form of holder.

Referring to the drawings, the numeral 1 designates generally a spark plug consisting of the usual stationary electrode 2 and adjustable electrode 3.

My improved attachment consists of a

conical protecting cap 4 that is formed of some suitable light metal and provided at its larger end with two rows of circumferential spaced apertures 5 which are designed to permit the gases of the engine cylinder to be ignited. The cap 4 is also provided upon opposite sides with longitudinal slots or apertures 6 that are disposed adjacent the larger extremity of the 60 cap and adapted to receive the securing arms of the holder which will be later more fully described. I also provide notches or recesses 7 that are arranged opposite to each other and disposed at the edge of the larger 65 portion of the cap 4. These notches or recesses 7 are designed to receive the portions of the stationary electrode 2 that are disposed adjacent to the edges of the cap 4 at the large extremity thereof. The conical 70 cap 4 is closed at its apex portion and open at its larger end as will be readily seen with reference to the drawings. As a means for holding the cap 4 in position upon the spark 75 plug 1 I provide a holding member comprising a split ring or approximately cylindrical body portion 8 that is preferably formed of some suitable resilient material 80 and provided at one end with diametrically opposed bendable securing tongues or arms 85 9. The holder 4 is arranged within the lower hollow portion of the spark plug 1 with its tongues 9 disposed outwardly beyond the lower edge of the spark plug. The body portion 8 in being split and formed of 90 resilient material is as will be readily seen held within the spark plug. The tongues 9 are inserted through the slots or apertures 6 of the conical cap 4 and bent so as to lie in a position whereby the cap 4 will be 95 readily secured and the tongues are not in a position to interfere with the usual function of the spark plug.

It will be readily seen that the cap 4 completely covers the lower extremity of 100 the spark plug, that is particularly the point where the spark takes place relative to the electrodes 2 and 3. The perforations or apertures 5 provide for the proper ignition of the gases but do not permit the accumulation of carbon upon the electrodes.

It will be readily seen with reference to the foregoing description and accompanying drawings that I have provided a simple and inexpensive attachment for spark 110 plugs which will permit the proper performing of the functions of the plug and

prevent the accumulation of carbon and other foreign matter due to the firing of the combustible charges within the cylinder, upon the electrodes of the spark plug. It 5 is preferable to cut off the excess length of the tongues 9 after the proper fitting of the cap 4 is had.

With reference to Fig. 5 wherein I have 10 illustrated a slightly modified form of holder, the holder consists of a cylindrical body portion 10 similar to the one 8 and provided with securing tongues 11 similar to the ones 9. I provide in this modified 15 form an upstanding lug 12 adjacent the outer end of the body portion 10 which is provided at its outer end with a preferably V-shaped notch 13. This form is used in connection with plugs wherein the stationary electrodes do not completely extend 20 across the hollow lower end or inner end of the spark plug.

When the attachment is in assembled position it will be readily seen with reference 25 to the foregoing description and accompanying drawings that the conical cap 4 is firmly held in engagement with the lower portion of the spark plug 1 through the medium of the tongues 9 carried upon the holders described.

30 The notches or recesses 7 formed in the cap 4 permit the snug fitting of the cap 4 relative to the plug.

In reduction to practice, I have found 35 that the form of my invention, illustrated in the drawings and referred to in the above description, as the preferred embodiment, is the most efficient and practical; yet realizing that the conditions concurrent with the adoption of my device will necessarily 40 vary, I desire to emphasize the fact that various minor changes in details of construction, proportion and arrangement of parts may be resorted to, when required, without sacrificing any of the advantages of my invention, as defined in the appended claims.

45 What is claimed is:—

1. An attachment for spark plugs comprising a hollow cap having one end open and adapted to fit upon the lower end of a 50 spark plug to cover the electrodes thereof, said cap being provided with rows of spaced perforations adjacent its open end and having diametrically opposed slots therein and

means for securing said cap comprising a cylindrical body portion arranged to fit 55 within a spark plug and a pair of spaced arms carried by said body portion and adapted to be inserted through the slots in said cap and to be bent over to engage the outer surface of said cap. 60

2. An attachment for spark plugs comprising a hollow cap having one end open and adapted to be secured to the lower end of a spark plug to cover the electrodes of said spark plug, said cap having rows of 65 spaced perforations adjacent its open end, an opposed slot formed therein, a cylindrical body portion arranged within the spark plug, bendable securing tongues carried by said body portion and adapted to be inserted 70 through the slots in said cap to secure said cap, and a lug formed adjacent the outer edge of said body portion and being provided with a V-shaped notch to receive one of the electrodes of said spark plug. 75

3. An attachment for spark plugs comprising a hollow cap having one end open and being provided adjacent its open end with rows of spaced apertures, said cap having diametrically opposed slots therein 80 adjacent the open end thereof and designed to cover the electrodes of a spark plug and means for securing said cap to the lower end of a spark plug comprising a resilient cylindrical body portion and a pair of bendable 85 opposed tongues formed on one end of said body portion and to extend through the slots in said cap and being bent to engage the outer face of said cap.

4. An attachment for spark plugs consisting of a hollow conical cap having one end open and to be secured adjacent to the lower end of a spark plug to cover the electrodes thereof, said cap having parallel rows of 90 spaced perforations formed therein adjacent to its open end, a split cylindrical resilient body portion arranged within the spark plug and bendable arms carried by the body portion to coöperate with the cap to hold the cap in position. 95

In testimony whereof I affix my signature in presence of two witnesses.

100 EMILE ROLLE.
